 York, N. Y., a corporation of New York

Application December 13, 1941, Serial No. 422,840

14 Claims. (Cl. 29—240)

This invention relates to wrenches, and more particularly to apparatus for separating threaded inserts from molded telephone key handles.

In the molding of plastic articles with internal threads, the molds frequently include threaded elements serving to form threads in the molded articles. Such threaded articles must necessarily be removed from the molded articles and it has been deemed advantageous to remove the elements from the molded articles before the articles have had sufficient time to cool and shrink on the elements.

An object of the invention is to provide a wrench which is simple in structure and highly efficient in operation, to cause relative rotation of articles.

With this and other objects in view, one embodiment of the invention comprises a wrench for threadedly connected articles including members to grip one of the articles and position the article, threadedly connected thereto, relative to a driven unit, the latter being rendered effective through movement of the gripping members to cause relative rotation of the articles.

Other objects and advantages will be apparent from the following detailed description when taken in conjunction with the accompanying drawings, wherein

Fig. 1 is a vertical sectional view of the wrench, portions thereof being shown in elevation;

Fig. 2 is a substantially horizontal sectional view taken along the line 2—2 of Fig. 1;

Fig. 3 is a top plan view of the wrench;

Fig. 4 is a fragmentary sectional view taken along the line 4—4 of Fig. 3;

Fig. 5 is an enlarged fragmentary detailed view of a rotary portion of the wrench;

Fig. 6 is an enlarged fragmentary top plan view of a portion of the article holding structure;

Fig. 7 is a vertical sectional view taken along the line 7—7 of Fig. 6;

Fig. 8 is a front elevational view of the threadedly connected articles, one of which is shown in section;

Fig. 9 is a fragmentary detailed view of another embodiment of the rotary portion of the wrench; and

Figs. 10 and 11 are fragmentary detailed views of another embodiment of the rotary portion of the wrench.

Referring now to the drawings, attention is first directed to Figs. 1, 2 and 3, which illustrate a housing 10, of the contour illustrated, includ-

ing a cover member 11 forming the upper wall of the housing. The member 11 is bent through an arc, at 12, extending downwardly, providing a supporting wall 14 extending at an angle from a horizontal plane but at right angles with respect to the portion covering the housing, this member then extending through an arc 15 and providing a base portion 16. Spaced uprights 17 extend from the side of the base portion 16 to points at the housing 10, where they are secured, these uprights serving as reenforcing means for the housing.

A motor 20 is mounted upon the wall 14 of the member 11, as illustrated in Fig. 1, the motor 15 having a shaft 21 extending into the housing 10 and provided with a pulley 22 fixed for rotation therewith. At the curved portion 12 of the member 11, an opening is provided for the mounting of a switch housing 23, a switch 24 being mounted therein and controlled by a switch handle 25. The switch 24 is disposed in an electrical circuit (not shown) including the motor 20, the switch controlling the circuit to effect starting and stopping of the motor and if desired, reversing of the motor.

A belt 28 for the motor pulley 22 extends around a wrench pulley 29, the latter having a hub disposed concentric with a bearing 30. The bearing is supported in an annular member 31, the latter extending through an opening 33 in the member 11 and fixed to a shiftable plate 34 by suitable means such as screws 35.

The shiftable plate 34 is circular in general contour except for an integral projection 36 which is apertured to receive a pivot element 37 which is in the form of a bolt. Furthermore, a handle 38 is fixed to the plate 34 at a portion diametrically opposed the integral projection 36. Through the aid of the handle 38, the plate 34 may be shifted from one position to another, these positions being called operative and inoperative positions due to the fact that the belt 28 is tightened on the pulley 29 in the operative position and made loose on the pulley when in the inoperative position. The opening 33 in the cover member 11 is of sufficient size to allow movement of the annular member 31 therein from one position to the other. A pin 40 carried by the annular member 31, is positioned to ride on the under surface of the wall member 11 to serve in guiding the shiftable mechanism of the wrench.

An annular cam 43, with roller receiving compartments 44 (Fig. 5) therein of the contours shown, is disposed concentric with the pulley 29.

The compartments 44 have cam-like surfaces 45 adjacent which gripping rollers 46 are disposed. The rollers as well as the compartments are disposed at equally spaced positions about the center of the cam 43, each roller having a compression spring 47 tending to move it inwardly to a position where it is under the control of the cam. The springs 47 are housed in apertures 48 in the cam and are removably held in place by screws 49. The rollers 46 have reduced end members 50 which are disposed in elongate apertures 51 of control members 52 and 53, these members being disposed upon each side of the cam 43 and secured with the cam to the pulley 29 by the aid of rivets 54. Therefore, the cam with the rollers and the controlling members are rotated with the pulley 29.

When the plate 34 of the associated mechanism is in the inoperative position, the pulley 29 is positioned in engagement with a stationary brake member 56, the forward portion of which is of a contour to interengage the groove of the pulley to create a sufficient frictional force to stop rotation of the pulley. The brake member 56 is adjustable between stationary guides 57 (Fig. 2) and secured in any desired adjusted position by means of a screw 58, the latter extending through an elongate opening 59 in the lower portion of the housing 10.

Attention is now directed to another aperture 60 in the lower wall of the housing adjacent the pulley 29, the latter having an opening 61 therethrough so that articles may drop through the opening 61 in the pulley, the aperture 60 in the housing, and into a container 62 supported by the base portion 16.

In the present embodiment the articles for which the wrench was designed, include a plastic handle 65 (Fig. 6) molded in a suitable mold (not shown), a portion of which, however, is an element 66 having a threaded portion 67, the purpose of the latter being to form internal threads in the handle 65 during the molding process. A locating element 68, extending vertically from an integral base 69, has a surface 70 of a contour conforming to the article 65, for the purpose of locating the article, with the element 66 thereattached, in the rotary unit of the wrench. The base 69 of the locating element is annular in general contour and is disposed in a circular recess in the plate 34, where it is secured in place, the central aperture of the base member allowing the element 66 to project therethrough as illustrated in Fig. 1.

Means is provided to grip the article 65 and to hold the article against rotation during rotation of the cam 43 and the associated mechanism, to cause removal of the element from the article. This means includes a pair of arms 71 pivotally supported upon the pivot element 37 and having supporting members 72. The supporting members 72 have opposing guideways 73 therein to receive companion gripping elements 74, the latter recessed at 75 to receive the article 65 and normally held in place by spring pressed plungers 76. The gripping elements 74, when gripping the article 65, will be spaced a sufficient distance apart to allow for the locating element 68. Each arm 71 is provided with a handle 77 arcuate-shaped in cross section to conform to the handle 38 which is circular in cross section. The arms 71 are normally urged outwardly by spring pressed ball members 78, the latter receiving their force from a common spring 79 housed in a member 80 mounted upon

the plate 34. The arms 71 are further under the control of a transverse member 81 extending across the arms, to allow movement of the arms away from each other but to limit such movement. The ends of the member 81 are supported by spacing members 82 through the aid of screws 83 threadedly connected to the plate 34.

An air controlled valve 84 is mounted upon the housing and includes a plunger 85 positioned to be actuated by the adjacent arm 71 when the latter is in its open or normal position. The adjacent arm thus functions to open the valve, which is in an air line 86, to allow air under pressure to pass through an air line 87 and a nozzle 88 against the article 65, to blow the article free of the wrench when released by the gripping elements 74, it having been freed of its element 66. The nozzle 88 is supported by a bracket 89 mounted on the member 81, the air line 87, or a portion thereof, being flexible to allow movement of the nozzle 88 with the other movable structure about the pivot 37.

During the operation of the apparatus, the arms 71 are normally in their outward positions (see dot-dash lines in Fig. 3) and are located with the plate 34 and the associated mechanism in the inoperative position. In this position the pulley 29 engages the brake member 56 to hold the rotatable wrench mechanism against rotation. At this time, the article 65 with the element 66 thereattached, may be located in the wrench through the aid of the locating element 68, the element 66 having been lowered through the aligned apertures of the base 69, the members 52 and 53, and the cam 43, the lower end of the element 66 extending into the central opening 61 of the pulley 29. When the article 65 with its element 66 are thus disposed in the wrench, the operator may grip the handles 77 to move the arms 71 about their pivot 37 toward each other, to bring the gripping elements 74 into the positions where the recesses 75 thereof will receive the article and grip the article to hold it against rotation. The gripping of the article causes partial compression of the springs, backing the plungers 76, effecting frictional holding of the elements in their normal lower positions, yet permitting upward movement of the elements. The handles 77 are thus disposed adjacent the handle 38, making it possible for the operator to move the plate 34 with the arms 71 about the pivot element 37, into the operating position.

Due to the fact that the pivot element 37 is disposed off center with respect to the motor shaft 21, the pulley 29 is moved through an arc away from the pulley 22, resulting in the tightening of the belt 28 to operatively connect the rotatable portion of the wrench mechanism with the power means, namely the motor. The tightening of the belt 28 on the pulleys 22 and 29 effects rotation of the pulley 29 in a clockwise direction (Fig. 2), rotating with the pulley the cam 43 and the control members 52 and 53. The rotative force of the cam 43 urges the rollers 46 into engagement with the element 66. The resisting force of the element 66, due to its threaded connection with the article 65, tends to increase the gripping force between the rollers and the element through the cooperation of the cam-like surfaces 45, resulting in rotation of the element with the cam. It is, therefore, apparent that through the assistance of the springs 47 in positioning the rollers, and the relationship of the cam surfaces 45 with the rollers, the greater the

holding force between the element 66 and its article 65, the greater will be the gripping force between the rollers and the element to effect rotation of the element. This effect continues during the unscrewing of the element from the article and due to the fact that the article is held against movement, the element is forced downwardly in a self-ejecting action so as to drop freely from the rollers 46 and through the opening 61 in the pulley 29, once the driving force has terminated. In other words, the positive downward force of the unscrewing action acting against the less positive frictional holding of the roller action, causes downward ejection of the element 66. Furthermore, the gripping force on the element is proportional to the amount of turning resistance offered and this gripping force releases as soon as the resistance to the unscrewing action ceases. The springs 47 function only to position the rollers ready to grip the element under the control of the cam but do not impart sufficient holding force through the rollers to the element to overcome the force of gravity on the element. Thus the element will drop by gravity into the container 62 once it is free of the handle or article 65.

After the element 66 has been removed from the article 65, the operator may return the plate 34 with the associated rotatable mechanism of the wrench to the inoperative position, moving the rotating pulley 29 into engagement with the brake 56, effecting stopping of the pulley together with the associated mechanism including the cam 43 and the rollers. The operator may then release the handles and in doing so, the spring 79 will be rendered effective to move the ball members 78 outwardly, spreading the handles to their normal positions to free the article 65 and to actuate the plunger 85 of the valve 84, to cause a jet of air under pressure to force the article free. The plunger 85 of the valve may be so positioned that it will be operated prior to the complete releasing of the article by the gripping elements 74.

It will, therefore, be apparent, by viewing the drawings, that by placing the article 65, with an element 66 attached, in the position shown in Fig. 1, the article will be automatically located by the locating element 68, at which time the operator may grip the three handles, that is the pair of handles 71 and the handle 38, this gripping action closing the arms to cause the gripping elements 74 to grip the article. After the operator has gripped the handles he then moves the handles clockwise a distance determined by the resistance caused by the tightening of the belt. The time necessary to hold the handles in the last mentioned position may be determined by the dropping of the element 66 into the container or by the estimated time necessary for the removal of the element. Thus the operator, after locating the article with the element, need only grip the handles, moving the handles into operating position, hold them there for a predetermined length of time, and return the handles to the normal position, where they are released.

This action causes first the gripping of the article and then effects rotation of the rotatable mechanism of the wrench, including the cam 43 and its rollers 46, to unscrew the element from the article, which action effects simultaneous ejection of the element from the rotatable means of the wrench. Furthermore, the operator need not wait after each operation for the rotatable means of the wrench to idle to a stop, this mechanism being stopped almost instantaneously by

the brake 56 when the pulley 29 is moved into engagement therewith. During normal operations, after the first relative movement of the article 65 and its element 66 when the maximum force is required to break the hold of the threaded connection therebetween, but little force is required to hold the element for continued rotation thereof. However, occasions may arise when the threaded connection may be tight all the way through the operation. In such instances the maximum holding force of the rollers on the element 66 would tend to oppose the ejecting movement of the element. At such times the gripping elements 74 may move upwardly with the article 65 against the holding force of the spring pressed plungers 76.

The embodiment of the invention thus described relates to the separating of two threadedly connected parts. If desired, the apparatus may function to threadedly connect two parts. The only change necessary to condition the wrench for this purpose is to make it possible for the rotation of the rotatable mechanism of the wrench in the opposite direction and the conditioning of the cam and the rollers to grip one of the parts when rotated in the said direction. This may be accomplished by reversing the direction of rotation of the motor. If the motor is of the reversible type the switch 24 may also be of the type to effect such reversal of the motor. Therefore, the change in the cam may be as illustrated in Fig. 9. In this figure a cam 90 is shown with recesses 91, to receive rollers 92 having reduced ends 93 which may also be controlled by members with elongate or similarly-shaped apertures, such as the members 52 and 53. In the recesses 91 there are cam surfaces 94 and 95 adapted to cause movement of the rollers toward the axis of the cam when the cam is rotated in either direction. Furthermore, each cam roller is provided with a pair of springs 96 of the compression type, each functioning to assist the roller for movement on its respective cam surface to effect gripping of the element depending upon the direction of rotation of the cam. Therefore, with the cam 90 and its rollers 92 substituted for the cam 43 and its respective rollers, the wrench would be conditioned to effect rotation of an element relative to an article in one direction, to threadedly connect the element with the article or to rotate the element in the opposite direction, to accomplish the same result which is possible with the cam 43, namely the separating of the threadedly connected element and article. In either case, the gripping force of the rollers on the element will vary with variations in the force necessary to cause rotation of the element relative to the article, the maximum force usually being required at the beginning of the separating operation and at the end of the assembling operation. At other times the gripping force is automatically reduced to allow axial movement of the element either for assembly with the article or for ejection therefrom.

The embodiment of the invention shown in Figs. 10 and 11 includes a structure which may be substituted for the annular cam 43, its rollers 46 and the control members 52 of the structure shown in Figs. 1 and 5. In the structure shown in Fig. 10, a cam 100 has a plurality of radially disposed recesses 101 which are identical in structure and provide cam-like surfaces 102. Rollers 103, substantially identical in structure to the rollers 46, are disposed in the recesses and

provided with reduced ends 104, these ends being disposed in elongate apertures 105 of control members 106. Fig. 11, which is taken along the line 11—11 of Fig. 10, illustrates the control members 106 disposed one upon each side of the cam 100, these members being secured together by connecting rods 107 spaced radially about the centers of the control members and extending through their respective recesses 101 in the cam. The outer ends of the connecting rods 107 are riveted in place to their respective control members, the portions of the rods disposed in the recesses of the cam being flattened, as shown in Fig. 10 and further illustrated in Fig. 11, so as to allow room for their respective rollers 103 to rotate freely. A helical compression spring 108 is provided for each of the connecting rods 107, these springs being disposed in their respective apertures 109 formed in the cam 100 and held in place by screws 110, the inner ends of the springs abutting against their respective connecting rods. Annular members 111 and 112, centrally apertured to receive the control members 106 for rotation of the control members therein, are disposed upon their respective sides of the cam 100. Sets of aligned apertures are provided in the cam 100 and the members 111 and 112, to receive rivets 114, similar in structure to the rivets 54 (Fig. 1), for the purpose of securing the structure to the pulley 29.

With the operation of the structure shown in Fig. 1 in mind, the same operations may be performed should the structure shown in Figs. 10 and 11 be substituted for the aforementioned cam 43, members 52 and 53 and the rollers 46. The distinguishing differences between the two structures, that shown in Fig. 1 and the embodiment shown in Figs. 10 and 11, lie in the controlling of the rollers shown in the two embodiments. With the structure shown in Fig. 1, the rollers 46 may grip elements of varying contours and if desired, these rollers, instead of being truly cylindrical, may be suitably convexed to assure gripping of articles of varying contours. The structure shown in Figs. 10 and 11 was particularly designed to maintain the axes of the rollers in parallel planes to assure contact of the rollers for their full length with a cylindrical element, and to further maintain the axes of the rollers in planes parallel with the axis of the element. This is assured through the positioning of the apertures 105, they extending toward the center of the cam, their positions being substantially radial therefrom. Another important function lies in the maintaining of the rollers at equally spaced positions about an element to be associated therewith, to further maintain the axis of the element parallel with the axes of the rollers by assuring contact of the rollers at equally spaced positions about the element. Therefore, due to the fact that the rollers can only move substantially radially with respect to the center of the cam, the control members 106 must be adapted to move about the axis of the cam and relative to the cam to bring about the gripping and releasing of the rollers with respect to the element or article they are gripping. The springs 108 function similarly to the springs 47 to locate the rollers so that they may grip an element through their association with their respective cam surfaces 102 when an element is disposed between the rollers and the apparatus is set in operation. In the structure shown in Figs. 11 and 12, the springs do not contact the rollers but engage the connecting rods

107 and control the rollers, through the control members 106, and apertures 105 functioning to move the rollers simultaneously, keeping them equally spaced about the element yet allowing movement toward or away from the element as controlled by their respective cam surfaces.

Although specific improvements of the invention have been shown and described it will be understood that they are but illustrative and that various modifications may be made therein without departing from the scope and spirit of this invention as defined by the appended claims.

What is claimed is:

1. A wrench, for separating articles having threadedly connected portions, comprising a unit mounted for rotation and for movement from a loading position to an operating position, gripping elements actuatable to hold one of the articles against rotation and support the other article in the unit, means at the operating position to cause rotation of the unit, and means in the unit to engage the article therein and cause rotation thereof with the unit to effect separation of the articles.

2. A wrench, for separating articles having threadedly connected portions, comprising a unit mounted for rotation and for movement from a loading position to an operating position, gripping elements actuatable to hold one of the articles against rotation and support the other article in the unit, means at the operating position to cause rotation of the unit, means in the unit to engage the article therein and cause rotation thereof with the unit to effect separation of the articles, and means at the loading position to stop rotation of the unit.

3. A wrench, for separating articles having threadedly connected portions, comprising a unit mounted for rotation and for movement from a loading position to an operating position, gripping elements actuatable to hold one of the articles against rotation and support the other article in the unit, means at the operating position to cause rotation of the unit, and means in the unit rendered effective upon rotation thereof to engage the article therein and cause rotation of the said article with the unit to effect separation of the articles.

4. A wrench, for separating articles having threadedly connected portions, comprising a unit mounted for rotation and for movement from a loading position to an operating position, gripping elements actuatable to hold one of the articles against rotation and support the other article in the unit, means at the operating position to cause rotation of the unit, means in the unit to engage the article therein and cause rotation thereof with the unit to effect separation of the articles, and means to cause movement of the unit from one position to the other.

5. A wrench, for separating articles having threadedly connected portions, comprising a unit mounted for rotation and for movement from a loading position to an operating position, gripping elements actuatable to hold one of the articles against rotation and support the other article in the unit, means at the operating position to cause rotation of the unit, means in the unit to engage the article therein and cause rotation thereof with the unit to effect separation of the articles, and means to cause simultaneous movement of the gripping elements and the unit from one position to the other.

6. A wrench comprising a unit mounted for rotation and for movement from a loading posi-

tion to an operating position, actuatable means in the unit adapted to receive a threaded article at the loading position and cause rotation of the article at the operating position, gripping elements actuatable to hold another threaded article against rotation with the article in the unit, means to move the elements and the unit to move the held articles simultaneously from the loading position to the operating position, and means at the operating position to cause rotation of the unit and actuation of the said actuatable means to cause separation of the articles.

7. A wrench comprising a unit mounted for rotation and for movement from a loading position to an operating position, actuatable means in the unit adapted to receive a threaded article at the loading position and cause rotation of the article at the operating position, gripping elements adapted to hold another threaded article against rotation with the article in the unit, means to move the elements and the unit to move the held articles simultaneously from the loading position to the operating position, and means at the operating position to cause rotation of the unit in either direction to cause assembly or separation of the articles.

8. A wrench, for separating first and second articles having threadedly connected portions, comprising a rotatable unit having a central aperture for receiving the first article, gripping rollers spaced about the aperture, and cam portions adapted to cause the rollers to move toward and grip the first article when the unit is rotated, gripping elements actuatable to hold the second article against rotation and locate the first article in the aperture of the unit in a position to be gripped by the rollers, means to cause rotation of the unit to cause separation of the articles, and means to support the gripping elements for movement thereof relative to the unit by the relative movement of the articles while being separated.

9. A wrench, for separating first and second articles having threadedly connected portions, comprising a rotatable unit having a central aperture for receiving the first article, gripping rollers spaced about the aperture, and cam portions adapted to cause the rollers to move toward and grip the first article when the unit is rotated, gripping elements actuatable to hold the second article against rotation and locate the first article in the aperture of the unit, means to cause rotation of the unit to cause separation of the articles, and means to normally support the gripping elements at locating positions and adapt the elements for movement away from the said positions by the second article during separation of the articles.

10. A wrench, for separating first and second articles having threadedly connected portions, comprising a rotatable unit having a central aperture for receiving the first article, gripping rollers spaced about the aperture, and cam portions adapted to cause the rollers to move toward and grip the first article when the unit is rotated, gripping elements actuatable to hold the second article against rotation and locate the first article in the aperture of the unit, supports for the gripping elements movable relative to each other to move the elements into gripping relation with the second article at a loading position and adapted to move the elements, articles and rotatable unit to an operating posi-

tion, and means at the operating position to rotate the unit to cause separation of the articles.

11. A wrench, for separating first and second articles having threadedly connected portions, comprising a rotatable unit having a central aperture for receiving the first article, gripping rollers spaced about the aperture, and cam portions adapted to cause the rollers to move toward and grip the first article when the unit is rotated, gripping elements actuatable to hold the second article against rotation and locate the first article in the aperture of the unit, supports for the gripping elements movable relative to each other to move the elements into gripping relation with the second article at a loading position and adapted to move the elements, articles and rotatable unit to an operating position, means at the operating position to rotate the unit to cause separation of the articles, and means at the loading position to stop rotation of the unit.

12. A wrench, for separating first and second articles having threadedly connected portions, comprising a rotatable unit having a central aperture for receiving the first article, gripping rollers spaced about the aperture, and cam portions adapted to cause the rollers to move toward and grip the first article when the unit is rotated, gripping elements actuatable to hold the second article against rotation and locate the first article in the aperture of the unit, supports for the gripping elements movable relative to each other to move the elements from open positions into gripping engagement with the second article, means to cause rotation of the unit to cause separation of the articles, and means actuated by one of the supports when the elements are in their open positions to eject the articles.

13. A wrench, for separating first and second articles having threadedly connected portions, comprising a rotatable unit having a central aperture for receiving the first article, gripping rollers spaced about the aperture, and cam portions adapted to cause the rollers to move toward and grip the first article when the unit is rotated, gripping elements actuatable to hold the second article against rotation and locate the first article in the aperture of the unit, supports for the gripping elements movable relative to each other to move the elements from open positions into gripping engagement with the second article, means to normally urge the supports and elements into the open positions, and means to cause rotation of the unit to cause separation of the articles.

14. A wrench, for separating first and second articles having threadedly connected portions, comprising a rotatable unit having a central aperture for receiving the first article, gripping rollers spaced about the aperture, and cam portions adapted to cause the rollers to move toward and grip the first article when the unit is rotated, gripping elements actuatable to hold the second article against rotation and locate the first article in the aperture of the unit, supports for the gripping elements movable relative to each other to move the elements from open positions into gripping engagement with the second article, means to normally urge the supports and elements into the open positions, means to cause rotation of the unit to cause separation of the articles, and means rendered effective by the returning of the supports to the normal positions to cause ejection of the second article.

YVES A. BOUGET.
